UNITED STATES PATENT OFFICE.

FRANK OSKRIT, OF PITTSFIELD, MASSACHUSETTS.

BOBBIN-HOLDER FOR SPINNING-SPINDLES.

970,745.

Specification of Letters Patent. Patented Sept. 20, 1910.

Application filed January 28, 1909. Serial No. 474,685.

To all whom it may concern:

Be it known that I, FRANK OSKRIT, a citizen of the United States, residing at Pittsfield, in the county of Berkshire and State 5 of Massachusetts, have invented certain new and useful Improvements in Bobbin-Holders for Spinning-Spindles, of which the following is a specification.

This invention relates to an improved 10 holder for securing the bobbin on the spindle of spinning machines, and comprises a detachable, adjustable spring sleeve frictionally secured to the spindle at a point near the lower end of the bobbin, and is so constructed and arranged as to effectually support the bobbin without projecting below the bottom of the same.

The rapid accumulation of threads around 20 the spindle below the bobbin due to the process of doffing necessitates their removal from time to time, usually by the aid of a sharp knife, and this manner of removal is considerably interfered with in all cases where a bobbin-holder is employed which 25 has any portion, particularly of metal, extending below the bottom of the bobbin and liable to contact with the blade of the knife. The present device is designed, therefore, to obviate this practical objection, and has, for 30 further objects, the provision of two separate planes of yielding engagement with the bobbin, each of which is independent of the other, and, also, in a holder wholly inclosed by the bobbin, of auxiliary means for preventing threads or other extraneous substances from working up within the same.

The invention consists in the construction, combination, and arrangement of parts, as 35 hereinafter described and claimed, reference 40 being had to the drawings, forming a part of this specification, in which like characters of reference indicate like parts in each of the views, and in which—

Figure 1 is a longitudinal sectional view 45 of a spinning spindle with a bobbin-holder thereon constructed in accordance with my invention, the bobbin being indicated in dotted lines; Fig. 2 is a detail perspective 50 side view of the holder; Fig. 3 is a similar view of the clamping collar; and Fig. 4 is a detail developed view of the body-portion 55 of the holder.

The specific form of embodiment of my 60 invention herein shown comprises a flat, 55 relatively thin, metal stamping which is bent into a tubular shape or sleeve and consists

of a plurality of longitudinally extended, vertical strips or springs 6 having their corresponding ends united by preferably integral cross strips or bands 7 and 9, the band 60 7 being provided with an integral outwardly-turned flange 8. When the stamping assumes a tubular form the ends of the bands 7 and 9 are respectively brought into 65 approximate free relation with sufficient space intervening to allow room for a slight, expansion or contraction when the holder is adjusted to the spindle 10. The springs 6 are then curved longitudinally outward and a collar 11 is drawn down over the sleeve to 70 a point somewhat above the middle thereof, the collar being of a predetermined size adapted to draw the springs 6 inward at this point, while those portions of the springs 75 above and below the collar are each provided with crowned centers adapted to separately engage the bobbin 5 when inserted upon the holder.

When the holder is placed over the spindle 10 it is drawn down to a point where it 80 firmly engages the spindle under the collar 11, the latter being made of such a diameter with reference to the tapering form of the spindle that the bottom of the holder, when 85 in operative position, is freely above the bottom of the bobbin. The ends of the holder at bands 7 and 9 are made somewhat larger 90 in diameter than the spindle at corresponding points so as to allow a free adjustment thereof when the springs 6 are extended by 95 the compression of the bobbin. The flange 8 at the bottom of the holder is designed to substantially close the opening intervening 100 the spindle and the inner walls of the bobbin for the purpose of preventing threads and other foreign substances from working up therebetween as before mentioned. Thus 105 it will be seen that in operation the collar 11 effectually supports the holder on the spindle and by its clamping engagement with the several springs at or near their centers separates them into two independent portions, either of which contributes support to the bobbin without the coöperation of the other. As the hole in the bobbin is graduated upward the upper portion of the holder 110 is made shorter, and consequently of less diameter at the crowned center than the lower portion, to correspond with the difference in the sizes of the hole in the bobbin at these 110 points.

I am aware that bobbin-holders of sheet-

metal construction have heretofore been devised. I do not, therefore, claim such construction broadly, but

What I do claim, and desire to secure by 5 Letters Patent, is:—

1. As an article of manufacture, a bobbin-holder adapted to be set over a spindle and comprising a metal sleeve formed with a plurality of longitudinally-arranged resilient elements, and a clamping device arranged centrally about the sleeve to secure the sleeve on the spindle whereby the portions of said resilient elements above and below the clamping device constitute independent spring sections for the support of 10 the bobbin.

2. A bobbin-holder adapted to be set over a spindle and wholly inclosed by the bobbin, comprising a spring sleeve having each 20 of its ends movable relatively to the spindle and adapted to be adjusted with relation thereto when the bobbin is set over the sleeve, and clamping means provided centrally on 15

the sleeve for securing the sleeve in position on the spindle, the portions of the sleeve 25 above and below the clamping means forming independent sections adapted to separately engage the bobbin.

3. As an article of manufacture, a bobbin-holder adapted to be set over a spindle 30 and comprising a metal sleeve formed with a plurality of longitudinally-arranged resilient elements and having an annular flange at its lower end adapted to close the space intervening the bobbin and the spindle, and a collar provided centrally about the sleeve for adjustably securing the sleeve in position on the spindle and adapted to form independent spring sections of said resilient elements above and below the collar. 35 40

In testimony whereof I hereunto affix my signature in presence of two witnesses.

FRANK OSKRIT.
